UNITED STATES PATENT OFFICE.

EDGAR L. WILLIAMS, OF PEORIA, ILLINOIS.

DESIGN FOR A GAME-BOARD.

SPECIFICATION forming part of Design No. 29,650, dated November 8, 1898.

Application filed October 14, 1898. Serial No. 693,557. Term of patent 3½ years.

To all whom it may concern:

Be it known that I, EDGAR L. WILLIAMS, a citizen of the United States, residing at Peoria, in the county of Peoria and State of Illinois, have invented a certain new Design 5 for a Game-Board; and I do hereby declare that the following is a full, clear, and exact description of the invention, which will enable others skilled in the art to which it applies to make and use the same.

In the appended drawings, Figure 1 is a plan view of the obverse side of the game-board. Fig. 2 is a perspective view of the reverse side, and Fig. 3 is a section through the center thereof.

The body of the board is square, having square corners, and is bounded by a rim which rises above the playing-fields on each side of the board, as shown. The playing-field on the obverse side (shown in Fig. 1) is raised and leaves a ditch between its edges and the raised rim. The rim is cut lower on this side of the board, as shown, to let the hand of the player come nearer the playing-surface. The corners of the board within the ditch are cut out to form openings and a net is secured in each to form a pocket which is used from either side. The said playing-field is provided at the center with a circular depression, also a circle concentric therewith, but considerably larger than said depression. Two arches are erected and cross each other above the said central depression, the ends thereof being bent downwardly and let into the board on the circle just described. A soft substance, such as rubber, surrounds the ends of the arches, and a button of like material is secured to the board upon the circle midway between the ends of

the arches. Near the edge of the playing-field is a line following the contour of said field and marks the base-line or line from which to shoot the disks or rings used in the game. Midway between the base-line and the circle are lines parallel with the sides or rim to form a square similar to the said base-line. At each corner of the square is a cushioned button like those previously described.

The reverse side of the board is perfectly plane within the boundary or rim, except for the corner apertures for the pockets referred to. A checkered space is located centrally on this side of the board and a base or playing line incloses same, but is some little distance therefrom. A circle is indicated in the center of the checkered space, within which are to be bunched the playing-disks. At all four edges of the board, with their bases resting against the rim, are six triangular spots, the apices of which reach within the base-line described. In one corner are a number of spots to indicate playing position and are arranged in triangular form, or with four spots in a line, then a row of three spots in front of them, then two spots, and, lastly, one spot, as in a ten-pin setting.

Having fully described my invention, what I claim as new, and desire to secure by Letters Patent, is—

The design for a game-board as herein illustrated and described.

In testimony whereof I affix my signature in presence of two witnesses.

EDGAR L. WILLIAMS.
